ACHILLE M. WILLIS, OF BEAVER, OKLAHOMA TERRITORY, ASSIGNOR OF
ONE-THIRD TO WILLIAM H. BROWNELL AND ONE-THIRD TO WILLIAM
McK. EVANS, OF RICHMOND, VIRGINIA.

OYSTER-BED.

No. 831,200.

Specification of Letters Patent.

Patented Sept. 18, 1906.

Application filed August 6, 1906. Serial No. 329,412.

To all whom it may concern:

Be it known that I, ACHILLE M. WILLIS, a citizen of the United States, residing at Beaver city, in the county of Beaver and Territory of Oklahoma, have invented a new and useful Oyster-Bed, of which the following is a specification.

This invention relates to oyster-beds of that general class shown and described in United States Letters Patent issued to me on the 24th day of July, 1901, under Serial No. 456,390.

The object of the invention is to improve the construction of the spawn-supporting mat by combining therewith a plurality of pivoted sections movable to closed position when the mat is elevated or withdrawn from the water, thereby to prevent accidental displacement of the oysters.

20 A further object of the invention is to provide a main supporting-cable having a plurality of secondary cables secured thereto and operatively connected with the mat and pivoted sections, respectively, whereby an initial upward movement exerted on the main cable will close or assemble the pivoted sections and a further movement of the cable elevate the spawn-supporting mat to permit the removal of the oysters.

30 A still further object of the invention is to generally improve this class of devices, so as to increase their utility, durability, and efficiency.

With these and other objects in view the invention consists in the construction and novel combination and arrangement of parts hereinafter fully described, and illustrated in the accompanying drawings, it being understood that various changes in form, proportions, and minor details of construction may be resorted to within the scope of the appended claims.

In the accompanying drawings, forming a part of this specification, Figure 1 is a perspective view of an oyster-bed constructed in accordance with my invention, showing the same resting on the bed of a stream. Fig. 2 is a similar view showing the pivoted auxiliary mats moved to operative or assembled position preparatory to elevating the mat.

Similar numerals of reference indicate cor-

responding parts in both of the figures of the drawings.

The improved device consists of a spawn- 55 supporting mat comprising a substantially rectangular frame 5, the side and end walls of which are connected by a plurality of longitudinal and transverse wires or bars 6 and 7. Interwoven between the wires 6 are pine 60 branches, brush, underwood, or other fibrous material 8, which forms a bed for the spawn, thereby preventing the same from being washed away by the action of the water.

Pivotedly associated with the frame 5 are a 65 plurality of movable sections or auxiliary spawn-supporting mats 9, also preferably covered with pine branches, as indicated at 10, the latter being interwoven between the longitudinal and transverse connecting- 70 wires 11, as shown. The pivoted sections 9, four of which are preferably provided, are each pivotally connected to the main supporting-frame 5 by means of suitable rings or loops 12, which embrace the adjacent bars of 75 the frame, and thus serve to secure the same together. As a means for raising and lowering the mat there is provided a cable 13, one end of which is connected to a suitable float 14, while the opposite end thereof is provided with a terminal ring 15. Secured to the ring 15 are a plurality of chains or cables 16, which extend to the corners of the main frame 5, there being similar chains 17, carried by the ring 15 and operatively connected with the pivoted sections 9, as shown. 80 It will thus be seen that an initial upward movement exerted on the cable 13 will move the pivoted sections 9 to vertical or operative position and that a further movement of 85 said cable will elevate the main frame 5 with the sections 9 in assembled position, thus preventing accidental displacement of the oyster during the elevating operation.

In use the spawn or seed-oysters are 95 placed on the bed proper and the latter lowered to the bottom of the stream and in which position the pivoted sections 9 will move laterally to open position, as best shown in Fig. 1 of the drawings, so that 100 the main and auxiliary spawn-supporting mats will be disposed in horizontal alinement with each other, there being sufficient slack left in the cable 13, so that should the cable

be struck by a passing boat said chain will give, and thus leave the bed undisturbed. When the mat is elevated, the upward movement on the cable will first move the pivoted sections to closed position, as shown in Fig. 2 of the drawings, after which the mat is brought to the surface of the stream and the oysters culled therefrom and the rest left undisturbed on the mat, which may then be lowered to the bottom of the stream. It will thus be seen that the improved bed may be used in depths too great for tonging or dredging and, in fact, may be used at any depth where the pressure is not too great for the oyster.

Having thus described the invention, what is claimed is—

1. A device of the class described, comprising a spawn-supporting mat having a plurality of auxiliary mats pivotally connected thereto and movable to closed position when the mat is elevated.
2. A device of the class described, comprising a spawn-supporting mat, a plurality of auxiliary mats pivotally connected thereto and movable to closed position when the mat is elevated; and fibrous material forming a part of the main and auxiliary mats.
3. A device of the class described, comprising a spawn-supporting mat having a plurality of auxiliary mat-sections pivotally connected thereto, a supporting-cable, and flexible connections between the supporting-cable and the main and auxiliary mats.
4. A device of the class described, comprising a spawn-supporting mat having a plurality of auxiliary mat-sections pivotally connected thereto; a main supporting-cable, a flexible connection between the main cable and the corners of the main supporting-mat, and a flexible connection between the auxiliary mat-sections and said cable.
5. A device of the class described, comprising a spawn-supporting mat, a plurality of auxiliary mat-sections pivotally connected thereto and normally disposed in horizontal alignment with the main mat-section, a sup-

porting-cable, and a flexible connection between the supporting-cable and the main and auxiliary mats, respectively, whereby when the cable is elevated the auxiliary mat-section will be moved to vertical position.

6. A device of the class described, comprising a spawn-supporting mat consisting of a rectangular frame connected by longitudinal and transverse stay-wires, auxiliary mats pivotally connected to the main mat and also consisting of the rectangular frames provided with longitudinal and transverse stay-wires, fibrous material interwoven between the stay-wires of the main and auxiliary mat-sections, a supporting-cable, and flexible connections extending between the supporting-cable and the main and auxiliary mats.

7. A device of the class described, comprising a spawn-supporting mat, a plurality of auxiliary mats pivotally connected thereto, a supporting-cable having a float secured to one end thereof and its opposite end provided with a terminal ring, and flexible connections extending between the ring and the main and auxiliary mats.

8. A device of the class described, comprising a spawn-supporting mat consisting of a rectangular frame provided with transverse and longitudinal stay-wires, auxiliary mats pivotally connected thereto and also provided with longitudinal and transverse stay-wires, fibrous material interwoven between the stay-wires of the main and auxiliary mats, rings forming the pivotal connection between said mats, a supporting-cable, and a flexible connection extending between the corners of the main and auxiliary mats and operatively connected with the supporting-cable.

In testimony that I claim the foregoing as my own I have hereto affixed my signature in the presence of two witnesses.

ACHILLE M. WILLIS.
